UNITED STATES PATENT OFFICE.

ALBERT E. JACOBSON, OF NEW YORK, N. Y.

PHOTOGRAPHICALLY-SENSITIZED MEDIUM.

1,219,739.

Specification of Letters Patent. Patented Mar. 20, 1917.

No Drawing.

Application filed December 7, 1915. Serial No. 65,572.

To all whom it may concern:

Be it known that I, ALBERT E. JACOBSON, a citizen of the United States, and a resident of the borough of Manhattan, city, county, and State of New York, have invented certain new and useful Improvements in Photographicly-Sensitized Mediums, of which the following is a specification.

This invention relates to a sensitized paper commonly known as "Japanese tissue" for use in the art of photography, and to the method of making the same.

One of the objects of the invention is to produce a paper of the character above specified which may be used either as a negative or positive upon which the photographic pictures are displayed.

Another object is to produce an integral non-separable photographic paper or film.

Other objects will appear from the hereinafter description and claims.

I have produced a new and very useful photographic film, sensitized with rapid printing silver emulsions consisting of silver bromid, bromo-iodid, chloro-bromid and chlorid to be used either for negatives or for positives, and also for contact printing and enlarging by either natural or artificial light.

This new product is based upon the discovery that the light sensitive emulsion may by absorption, be embodied in the base or support in one integral non-separable body. By this, I mean that the support or base and light sensitive emulsion forms one integral whole as contradistinguished to those products in which the emulsion and the support are superimposed, the emulsion being kept on the surface of the support as commonly produced in the case where plates or celluloid films and papers are used.

I have discovered that the paper commonly known in the art as Japanese tissue is best adapted for use in my invention and this kind of paper is preferably used by me.

The method of sensitizing the Japanese tissue film and the results and advantages obtained thereby and the product thus produced, will now be described.

I take a piece of Japanese tissue and spread thereupon with a brush the warm, light sensitive emulsion and permit the emulsion to be absorbed into and through the fibers of the tissue, thereby causing the light sensitive emulsion and the tissue to form one

integral non-separable body or film, thereby producing the desired result in one operation, as distinguished from the usual methods of first sizing and then sensitizing the paper.

Any superfluous emulsion on the surface of the tissue is removed by means of another brush and then the sensitized tissue is hung by one end in a cool chamber to chill the gelatin until it becomes dry.

The sensitizing must be done in a dark room by ruby or other non-actinic light.

The Japanese tissues being very thin, absorb only a sufficient quantity of the emulsion to produce a brilliant image. As the emulsion is practically on both sides of the Japanese tissue film, it can be exposed or printed on either side.

By the use of my invention, no blisters are formed, neither does it frill or separate from the support during the manipulations of developing, fixing and washing the print or negative. The print dries quickly between blotters under mild pressure and remains flat and flexible and cannot break. It retains the rich, silky surface characteristic of the Japanese tissues and a print or enlargement produced on the Japanese tissue film has an extremely beautiful appearance and pleasing effect and in appearance is greatly unlike an ordinary photograph, as it has a marked resemblance to an etching. By reason of the fibers of the tissue, an advantage accrues by diffusion of the coarse retouching on portrait negatives, thereby saving the time of the artist. The negative or print is durable and permanent as the fibers of the tissue protect the minute silver particles of which the image consists, from deterioration from atmospheric action or otherwise. The emulsion may be applied with a brush as stated or by floating the tissue on the surface of the emulsion or the tissue may be entirely immersed in the emulsion or may be coated by means of a machine.

The Japanese tissue prints are capable of having water or oil colors directly applied on either side.

Having now described my invention, what I claim as new and desire to secure by Letters Patent is:

1. A photographically sensitized medium, consisting of a tough fibrous and porous tis-

- sue impregnated with a rapid printing silver emulsion distributed through the tissue and upon both sides thereof.
2. A photographically sensitized medium consisting of a Japanese tissue impregnated with a rapid printing silver emulsion distributed through the tissue and upon both sides thereof.
3. A photographicall sensitized medium consisting of a support of Japanese tissue, said support being impregnated with a rapid

printing silver emulsion which is distributed upon both sides thereof to form an integral non-separable whole.

In witness whereof I have hereunto set my hand at the borough of Manhattan, city and State of New York, this fourth day of December, 1915.

ALBERT E. JACOBSON.

In presence of—
ETHEL D. BARON,
ISABEL R. RICHARDS.
